FOLDING TABLE

Charles W. Sadenwater, Saginaw, Mich., assignor
to Saginaw Manufacturing Co., Saginaw, Mich.,
a corporation of Michigan

Application July 5, 1935, Serial No. 29,849

3 Claims. (Cl. 38—117)

This invention relates to folding tables of the kind having a top, such as an ironing board, with rear legs hinged thereto, and a front leg hinged at its upper end to the middle part of the board. Tie-rods connect the lower end of the front leg to the rear legs, and two diagonal braces are also hinged to the rear legs, their free ends adapted to be slidably guided along the front leg. The diagonal braces extend forwardly and upwardly, joining the board at the upper end of the front leg when the table is erected.

Folding tables of such character are known, but my present invention differs from earlier structures in several important features whereby new and useful results are attained.

An object is to reduce the amount of hand labor heretofore required in the manufacture of foldable tables of this class, enabling them to be fabricated in mass production at unusually low cost, yet having adequate strength and durability and being easy to fold and erect.

Another object is to provide a novel arrangement of the parts comprising the main joint structure. This joint is located near the center of the board and by means of it the front leg and the diagonal braces are made to act conjointly to releasably hold the table in its erected position.

A further object is to construct and arrange the legs and braces so they can be folded very compactly against the board, thus conserving space in packing the table for purposes of storage or shipment. Many earlier types of folding ironing tables have been objectionable because the diagonal braces when folded rested upon the front leg and consequently required a shipping container almost twice as deep as that required for the present improved structure.

With the above objects in view, and certain others which will appear later in the specifications, my invention comprises the devices described and claimed and the equivalents thereof.

Fig. 1 is a side view of an ironing table embodying my invention.

Fig. 2 is a part sectional side view of the main joint, assembled, one of the diagonal braces being removed, the section being taken on line 2—2 of Fig. 4.

Fig. 3 is a view of the bracket shown in Fig. 2, as seen from below.

Fig. 4 is a fragmentary plan view showing the free ends of the diagonal braces and the front leg, in folded position.

Fig. 5 is an end view of the parts shown in Fig. 4, in relation to the board.

Fig. 6 is a small scale, part sectional, diagrammatic side view of a modified form of the main joint bracket.

In the drawing like characters of reference indicate similar parts throughout all the views. 5

The ironing board 1 is equipped with the usual rear legs 2, pivoted at 3. Near the middle of the length of the board and secured centrally to the under side thereof is a main joint bracket 4, to which the front leg 5 of the table is pivoted, 10 at 6.

Pivotedly secured near the bottom end of the front leg, at 7, is a pair of connecting rods 8. The rear ends of rods 8 are pivoted to the rear legs 2 at points 9, intermediate their ends. 15

Diagonal braces 10 are secured to the pivots 9 and converge towards the bracket 4. The convergent ends of braces 10 are connected together in spaced relation by a bar 11, and also by a second bar 12, as shown in Figs. 2 and 4. Bar 11 20 is slidable along the front face 5a of the front leg 5, the second bar 12 is at the rear thereof, and the two bars are spaced apart as shown at S, Fig. 4. Bar 11 extends across the upper side of the diagonal braces 10, see Fig. 2, and the second or rearward bar 12 is beneath them. Each bar, 11, 12 is preferably made of a piece of metal rod bent into U-shape to present two legs or shanks 11a, 12a. The shanks are received in holes in the braces 10 and are held by washers 30 13, by riveting, or otherwise. Bar 12, however, being merely a guide member for leg 5, may be of any other desirable or convenient form, such as a suitably shaped piece of wood or a metal plate. 35

Considering now the mode of operation of the main joint and its associated parts when the table is to be unfolded and set up for use, the folded table is first stood on its rearward end and the free ends of rear legs 2 are pulled away 40 from the board 1 and downwardly. Bar 11 is thereby caused to slide along the front face 5a of the front leg 5 until it arrives at the main joint bracket 4, where it enters wide mouthed slots 14 which are provided, one in each side wall 45 of the bracket. The spacing S of bars 11 and 12 is such as to compel the bar 11 to enter the slots 14. Upon reaching the bottom of the slots the bar 11 is releasably held therein by means of a spring latch member 15 mounted on leg 5. Latch 50 15 is depressed by the bar 11 when it enters the slots, and when the bar arrives at the bottom of slots 14, the latch springs outwardly, as shown in Fig. 2. The assembled joint can not easily be sprung or racked and it provides a rigid durable 55

support that will not wear and become loose after long service, as has frequently been the case in earlier main joint structures that consisted of pins and bearings which, for reasons of cheapness, were usually made of wood and soon became worn.

To fold the table for storage, the latch 15 is depressed by hand, releasing bar 11, which is slid along the front leg 5 in a downward direction, indicated by the straight arrow in Fig. 1. The diagonally opposite locations, shown in Fig. 2, of the bars 11 and 12 relatively to the braces 10 and leg 5, allow the legs and brace members to be stowed compactly against the board, see Figs. 15 4 and 5, when the front leg 5 is rotated about its pivot 6 in the direction of the curved arrow, Fig. 2.

When thus stowed, the braces 10, leg 5, and bars 11, 12 occupy the positions shown in Figs. 20 4 and 5. It is seen that the front leg 5 lies flat against the under side of the board 1 and the two diagonal braces 10 also lie flat, one on each side of the front leg. Bar 11 is stowed between the 25 leg 5 and the board 1, and an outwardly offset portion of the second bar 12 lies across the outer face of the leg 5. The table thus folded can be put into a very thin package.

Preferably, the board 1, the legs 2, connecting rods 8, and braces 10 are all made of wood. The 30 main bracket 4 is of pressed metal and the two bars 11, 12 are preferably made from pieces of round wire.

In the modified form of bracket and joint shown 35 in Fig. 6 the bracket 4 per se, is not formed with the slot 14, as in Figs. 2 and 3, but instead its end 4a presents only one wall of such a slot. The opposite wall 4b is presented by a block 4c which is appropriately shaped and spaced from the bracket wall 4a, and is fixed to the board 1. The 40 modified form of Fig. 6 is introduced in this disclosure to show how a slot 14 may be produced by employing a somewhat simplified form of bracket that requires less metal in its manufacture, and to demonstrate that the slot element may be 45 provided by equivalent devices that perform the functions of slots 14, Fig. 2, embodied in a structure somewhat modified.

It will be observed that the bracket 4 and the bars 11, 12, and the spring latch 15, are the only metal parts, and that each of those parts is small and of extremely simple design, and consequently inexpensive, yet they co-operate to provide extraordinary stability and rigidity in the erected 5 table. They will not become worn and wobbly after long continued use, as has often been the case with joints that were made of wooden parts.

By the means above described I have produced 10 an extremely strong, rigid and durable main joint structure for folding tables of the character described. The simplicity of structure, ease of assembling and the small number of parts employed enable these tables to be produced in 15 quantities at very much lower cost than heretofore.

Having thus described my invention, what I claim and desire to secure by Letters Patent is:

1. A folding table including a board, rear legs 20 hinged thereto, diagonal braces hinged to said rear legs and convergent toward their free ends, a bracket secured to said board, and a front leg hinged to said bracket, having in combination, a bar fixed to the upper faces of said diagonal 25 braces adjacent their free ends and holding the braces in spaced relation, said bracket presenting slots aligned with the front face of said leg and adapted to receive said bar, and a second bar parallel with said first mentioned bar and spaced 30 therefrom, said second bar being secured to the lower faces of said braces, said front leg being slidably received in the space defined by said braces and bars.

2. A structure as set forth in claim 1 wherein 35 a latch member, associated with said front leg is arranged to normally keep the slots of said bracket closed against the removal therefrom of said first mentioned bar.

3. A structure as set forth in claim 1 wherein 40 the said slots present wide mouths and the spacing apart of said bars is such as to compel the first mentioned bar to enter said slots during the sliding movement of said braces relatively to said front leg.

CHARLES W. SADENWATER.
